Term of patent 14 years

Int. Cl. D10—06; D26—02

U.S. Cl. D10—114

FIG. 1 is a perspective view of an immersion responsive signal lamp embodying my new design;

FIG. 2 is a front elevation view of the immersion responsive signal lamp of FIG. 1;

FIG. 3 is a right side elevation view of the immersion responsive signal lamp of FIG. 1;

FIG. 4 is a left side elevation view of the immersion responsive signal lamp of FIG. 1;

FIG. 5 is a top plan view of the immersion responsive signal lamp of FIG. 1;

FIG. 6 is a bottom plan view of the immersion responsive signal lamp of FIG. 1; and

FIG. 7 is a bottom plan view of a second embodiment of my new design, it being understood that the second embodiment differs from the first only in the configuration of the bottom sensing element.

I claim:

The ornamental design for an immersion responsive signal lamp, as shown and described.
